UNITED STATES PATENT OFFICE.

WILLIAM S. BODLEY, OF LOUISVILLE, KENTUCKY, ASSIGNOR TO SUNLIGHT DOUBLE GLASS SASH COMPANY, INC., OF LOUISVILLE, KENTUCKY.

SASH FOR HOTBEDS AND OTHER PURPOSES.

1,079,631.

Specification of Letters Patent.

Patented Nov. 25, 1913.

Application filed January 7, 1910. Serial No. 536,882.

To all whom it may concern:

Be it known that I, WILLIAM S. BODLEY, a citizen of the United States, residing at Louisville, in the county of Jefferson and 5 State of Kentucky, have invented certain new and useful Improvements in Sash for Hotbeds and other Purposes, of which the following is a specification.

My invention relates to improvements in 10 glazed sash for hot beds, hot house roofs and skylights, and which may also be available for other glazed window sashes and doors.

The object of the present improvements 15 is to make such glazing completely or substantially air and water tight, and at the same time allow for the convenient and economical insertion of one or more panes as substitutes for those which may become 20 broken.

In order to make the invention more clearly understood I have shown in the accompanying drawings means for carrying the same into practical effect, without limiting 25 my improvements, in their useful applications, to the practical constructions which, for the sake of example, I have illustrated.

In said drawings—Figure 1 is a plan view 30 of a hot bed sash embodying the invention. Fig. 2 is a perspective view of a portion of the same, partly in section. Fig. 3 is a similar view of a slightly modified form of the invention. Fig. 4 is a similar view 35 showing another slight modification. Fig. 5 is a similar view showing a further modification. Fig. 6 is a sectional view showing the packing made with a bottom strip. Fig. 7 is a perspective view of the packing-holding 40 spring employed in the construction shown in Fig. 5. Fig. 8 is an inner face view of a portion of one of the muntins, showing the arrangement of the panes, the pane-holding springs and the pane-stop.

45 Referring to the drawings, 1 indicates the sash frame which, in the case of a hot bed sash, will ordinarily comprise stiles 2, a muntin or muntins 3, a top cross bar 4 and a bottom cross bar 5. These parts are 50 framed together in any usual or approved manner and are formed on their inner faces with grooves 6 to receive the edges of the glass panes 7, excepting that either the top bar or the bottom bar or rail 4 or 5, or 55 both, may be made narrower vertically so

as to be flush with the inner surface of the groove 6 of the stiles and muntins so as to permit of the longitudinal insertion of the panes, as described in my Patents No. 720,318, and No. 909,361. The glass panes 7 are inserted in the grooves 6 so as to overlap 60 one another, and are held from longitudinal movement in an upward direction by stops 8 which are or may be of the character described in my said Patent No. 909,361. The 65 panes are furthermore held against one another and against the lower or inner surfaces of the grooves 6 by springs 9, as described in the last mentioned patent, or by other equivalent or suitable means. 70

Under many conditions it is not necessary to make the sash completely water tight or air tight, but in other conditions and some climates, and where the sash is employed for skylights, windows, etc., an air and 75 weather tight construction is desirable or necessary. Accordingly my present improvements are directed to this end, without incurring the old difficulty in substituting a new pane for one which may have been 80 broken. This is accomplished by a packing, or a packing and putty combined, as herein-after described.

10 indicates a packing such as marline twine, cord, or compressible cylinders empty 85 or filled with soft substances, such as soft putty, or any other suitable packing material, either in short sections, or which extend for the full length of the groove 6, and which is preferably of an oily character. 90 This packing is applied above the edges of the panes 7 within the grooves 6, and over or above the stops 8 and either before or behind the springs 9 or other fastening devices of the panes. The packing may be 95 formed with a bottom strip 11 which is inserted across or beneath the outer edges of the pane. Outside of the packing 10 I preferably apply putty, as indicated at 12, which rests on the glass panes and has some engagement with the frame at the point 13, but which mainly or partly rests upon the packing 10. 100

The advantage of this construction and arrangement is that when a pane becomes 105 broken and it is necessary to replace it the putty above the broken pane may be easily removed without the difficulty and delay of digging it out of a deep groove or angle, the only point at which the putty requires to 110

be detached or scraped off being along the small portion of the frame at 13.

By making the packing of an oily character the putty is kept from drying out and cracking. This is accomplished by well impregnating the packing with oil before it is put in place.

In the drawings I have illustrated frames adapted to receive and hold two layers, an 10 inner layer and an outer layer, of glass panes, so as to leave an air space between them. It will be understood, however, that the improvements may be applied to frames having a single layer of panes.

15 In Figs 3 and 4 I have shown a sash frame in which the panes require to be inserted longitudinally along the grooves 6, as described in my said patent.

20 In Fig. 2 the flange 14 of the frame at the outer side of the groove 6 is shown as made shorter so that a pane may be inserted laterally between two opposing flanges 14 and worked into place without disturbing the putty at the ends of the grooves.

25 In Fig. 4 is illustrated a construction in which the panes have to be inserted longitudinally along the grooves 6, but this is made easy by the omission of the putty and the employment of the packing 10 only, the 30 panes being held in place by the stops 8 and springs 9 and the packing being wedged between the edges of the panes and the inner parts of the grooves.

In Fig. 5 a construction is shown in which 35 the outer flange of the groove 6 is dispensed with and the putty is applied over and around the packing, the panes of glass being secured in place by means of points or cleats or other suitable means, the putty being kept away 40 from the angle of the frame so that it may be readily removed and repairs easily made. In this construction the packing is preferably kept in place, and also the panes 7, by metal springs 15 which are attached to the 45 frame at 16, inclose the packing, bear on the top surface of the underlapped panes at 17, and bear laterally against the lower edges of the overlapped panes, the overlapped panes being held down by the packing, which is in turn confined by the springs 50 15. I further provide against leakage to the

interior of the hot bed or other inclosure by gutters 18 which are formed in the lower surface of the outermost groove 6. Any water which may leak past the edges of the 55 panes is received in the gutters 18 and conducted to the lower end of the sash. The gutter 18 may be made of any shape, width or depth desired, and may be placed anywhere on the bottom surface of the groove. 60 It may be made by adding a strip either of wood or metal to the wood-work on the said surface of the groove.

What I claim is:

1. In a sash for hot beds and other purposes, the combination of a grooved frame, panes of glass superposed so as to lap on each other and fitted in the grooves of the frame, a packing in the grooves superposed upon the panes and beneath the lip of the 70 groove without adhesion to the glass or to the frame, and means for holding the glass and packing in place consisting of putty arranged outside of the packing and having adhesion to the frame only upon the overhanging lip of the groove, substantially as 75 set forth.

2. In a sash for hot beds and other purposes, the combination of a frame, a pane or panes of glass therein, a packing of an 80 oily character superposed upon the glass and against portions of the frame, and putty applied against the glass and over the packing, substantially as set forth.

3. In a sash for hot beds and other purposes, the combination of a frame formed with longitudinal grooves 6 and flanges 14 exterior to the grooves, panes of glass fitted in the grooves, the panes being of a width greater than the distance between opposing 90 flanges 14, and a packing having a strip 11 fitted in the grooves above the panes with its said strip arranged at the edges of the panes and between the same and the bottoms of grooves. 95

In testimony whereof I affix my signature in presence of two witnesses.

WILLIAM S. BODLEY.
